SHARPENING DEVICE FOR SAFETY RAZOR
BLADES

William R. Daughtry, Birmingham, Ala.

Application October 2, 1929. Serial No. 396,873

8 Claims. (Cl. 51—84)

The present invention relates to improvements in sharpening devices for safety razor blades, one object of the invention being to provide a hand-operated device having a holding stock which 5 bodily carries a rotary sharpening member, a pivoted frame upon which is mounted the blade carriage, and a manually operated means for simultaneously rotating the roller and imparting reciprocating movement to the blade carriage, 10 thus insuring an even sharpening to the edge or edges of the blade, due to the movement of the blade upon the rotary member, and the rotation of the latter.

Another object of the present invention is to 15 provide a device of this character which is attractive in appearance, cheap in construction, and which is thoroughly efficient and practical in use.

With the foregoing and other objects in view, which will appear as the description proceeds, the 20 invention resides in the combination and arrangements of parts and in the details of construction hereinafter described and claimed, it being understood that changes in the precise embodiment of the invention herein disclosed can be made within 25 in the scope of what is claimed, without departing from the spirit of the invention.

In the accompanying drawing:—

Figure 1 is a side elevation of the complete device, a portion of the driving gear wheel being broken away, and dotted lines illustrating the 30 position of the blade carriage carrying frame when elevated.

Figure 2 is a top plan view of the complete device as illustrated in Fig. 1.

Figure 3 is an end view of the complete device, the stock being fore-shortened or broken away.

Figure 4 is a section taken on line 4—4 of Fig. 2.

Figure 5 is a top plan view of the central portion of a modified form of the present device, 40 wherein two parallel rollers are employed, and by means of which the two opposite edges of the safety razor blade are operated upon simultaneously.

Referring to the drawing, and more particularly to Figures 1, 2 and 3, the reference numeral 6 designates the stock of the present device and 7 represents a hand grip or handle therefor.

Anchored in the stock and extended in an opposite direction to the handle is an axle 8, the outer end of which is upwardly bent as at 9 to provide a right-angled arm 10 and a limiting hook 11, the purpose of which will presently appear.

Mounted for rotation upon the axle 8 is an 55 abrasive roller 12 which is adapted to be driven

by means of a gear 13 fastened to the inner end of said roller.

Rotatably supported by means of a stud member 14 carried by the stock 6, is a main gear wheel 15, whose teeth 16 are upon the inner face thereof and mesh with the gear 13 so that as the gear wheel 15 is rotated rotary motion is imparted to the abrasive roller 12. A pin 17 is carried by the gear wheel 15 and projects from the outer face thereof, and disposed thereon is a loop 18 of a connecting rod 19 of which one branch is longer than the other, the purpose of which will presently appear; while further carried by the pin 17 is an operating handle 20 by means of which the present mechanism may be manually operated. 70

A frame F, which is made of a single piece of wire and bent to provide two spaced parallel rods 21, is mounted for swinging movement through the medium of two coils 22 upon the portion 10 of the axle 8, so that the said frame may be 75 moved to assume the respective full and broken line positions as shown in Fig. 1.

The outer portions of the rod 21 are bent toward each other, and are coextensive as at 23 and terminate in a finger loop 24, while attached 80 to the stock 6 is a clip 25 which forms a latching means for engaging the portion 23 of the frame F to hold the same in operative position.

Mounted for sliding movement upon the parallel rods of the frame, is a blade carriage 26, 85 two openings 27 of which are of larger diameter and fit upon the rods 21, so that the carriage may be reciprocated freely upon these rods and longitudinally of the roller 12. In order that a safety razor blade of well-known type may be 90 properly attached and detached from the carriage, two springs 28 are secured to the carriage by a fastener 30 so that the notch terminals 29 of the springs may extend below the lower face of the carriage and enter the apertures of the 95 safety razor blade B, to engage the walls thereof so as to hold the blade in the position illustrated in both full and dotted lines in Figure 1, and thus to present one cutting edge as in Figure 2, 100 to and upon the abrasive roller 12.

In order that reciprocating movement may be imparted to the blade carriage 26, the longer branch 31 of the connecting rod 19 is provided with an L-shaped terminal 32, which is extended 105 through a transverse bore 33 of the carriage 26, and thus connects the carriage to said rod, so that when the handle 20 is turned to rotate the gear wheel 15, reciprocating movement is imparted to the carriage so that the blade is moved 110

back and forth, while the roller 12 is being rotated through the gears 15 and 13.

By this means the roller is rapidly rotated against an edge of the razor blade and a reciprocating movement is imparted to the carriage, thus stropping or honing the safety razor blade.

Where the gears 13 and 15 are employed, it is possible to use a friction between them, so that the speed imparted to the roller 12 may be regulated by the pressure upon the handle 20 in an inward direction during the rotation of the wheel 15, and thus provide a means whereby duller blades may be more efficiently sharpened, and those that do not need so much grinding may be operated upon with a lighter touch.

It is also apparent that the frame F may be bent outwardly or inwardly toward the roller or away therefrom so as to regulate the spring tension of the rods 21 relative to the carriage and the abrasive roller, so that the desired pressure of the blade upon the roller may also be regulated.

As shown in Figure 5, two rollers 12' and 12^a, may be employed, thus providing two abrasive members for simultaneously acting upon the two opposite edges of a safety razor blade, the axles 8' and 8^a being parallel and the terminal portion 10' common to both axles 8' and 8^a serving to retain the adjacent ends of the two rollers at a fixed distance from one another. The rollers 12' and 12^a are provided, respectively, with gears 13' and 13^a meshing with one another, so that when the gear wheel 15' is rotated it will rotate the abrasive rollers 12' and 12^a. Other elements are identical with the structure heretofore recited, so that corresponding parts are indicated by the same reference numerals primed.

From the foregoing description taken in connection with the drawing, the operation of the present device is readily understood, and its advantages fully appreciated, but briefly stated, it is as follows:—

The frame F is moved to assume the dotted line position in Figure 1 and the blade to be operated upon is then positioned on the carriage 26 with the notched terminals 29 of the springs 28 extending through the usual openings of the blade, the outward tension of the springs being such as to cause the notches to engage the walls of the openings of the blade and tend to hold the blade against the abutting surface of the carriage 26. The frame F is now lowered to bring the portion 23 of the frame into the clip 25, at which time the edge of the blade B is resting upon and engages the roller 12. The handle 20 is now turned to rotate the abrasive roller 12 and reciprocate the carriage 26 to sharpen one side of one edge of the blade. When this is completed, the blade is removed and reversed, and the other side of the same edge is operated upon; and where the blade is a double edge type, sides of the edge are sharpened in a similar manner.

With the construction shown in Figure 5 the same operation takes place, except that both cutting edges of one face of the blade are acted upon simultaneously, and only two operations are necessary instead of four as in the case when a double edge blade is sharpened by a single roller to complete the sharpening of both edges.

What is claimed is:

1. A sharpener of the class described having a sharpening roller, an inherently resilient frame substantially parallel to the axis of the roller, a blade carrier reciprocable along said frame and yieldingly urged toward the roller by the resiliency of said frame, means mounting said roller and

frame, and driving mechanism mounted on said means and operatively connected to the carrier and to the roller for simultaneously reciprocating the carrier and rotating the roller.

2. A safety razor blade sharpener having a rotatable abrasive roller, a resilient frame disposed parallel to the straight surface line of the roller, a blade holder mounted on said frame and reciprocable along said frame and yieldingly urged by the resiliency of said frame toward the roller, driving means including a crank for rotating the roller and simultaneously reciprocating the blade holder; and support means for the roller, the resilient frame and the driving means.

3. A safety razor blade sharpener comprising a rotatable abrasive roller, a frame including two resilient wires disposed adjacent the straight surface line of the roller and substantially parallel thereto, hinge means mounting one end of said frame and latch means adapted to hold the other end of said frame to a support, a blade holder reciprocably mounted on said frame and urged by said frame toward the roller, driving means including a crank for rotating the roller and simultaneously reciprocating the blade holder; and means mounting the roller, the driving means and the latch means.

4. A sharpener of the class described having a stock, an axle extending forwardly therefrom, a sharpening roller journaled on the axle, a resilient frame disposed parallel to said axle and located above the roller and laterally offset with respect to the axis thereof, said frame being connected to the axle and to the stock, gearing on the stock and roller to rotate the roller, a blade carrier mounted to reciprocate along said frame longitudinally of said roller and yieldingly urged by the resiliency of said frame toward said roller, and an operative connection between the gearing and said blade carrier.

5. A sharpener for safety razor blades comprising a stock, a stationary axle carried by said stock, an abrasive roller rotatably mounted on said axle, a resilient frame disposed parallel to the straight surface line of the roller, means hingedly supporting one end of said frame adjacent one end of said roller, means detachably securing the other end of said frame adjacent the other end of said roller, a blade holder mounted on said frame and reciprocable along said frame and urged by the resiliency of said frame toward the roller; and means including a crank rotatably mounted on said stock for rotating the roller and simultaneously reciprocating the blade holder.

6. A safety razor blade sharpener, including a stock provided with a hand-grip, a stationary axle having one end fixedly attached to said stock and provided at its other end with a right angled terminal, an abrasive roller rotatably mounted upon said axle, a manually operated prime mover carried by the stock, a cooperative means carried by the prime mover and the roller to rotate the roller from the prime mover, a swinging frame attached to the right-angled terminal of the axle and movable to and from the stock and roller, cooperative means carried by said frame and the stock for locking the frame in operative position, a blade carriage mounted for reciprocating movement upon and carried by said frame, and means connecting the carriage to the prime mover so that the carriage is reciprocated simultaneously with the rotation of the roller.

7. A sharpener of the class described having a stock, an axle extending forwardly therefrom, a

sharpening roller journaled on said axle, the forward end of said axle extending upwardly and thence laterally, a resilient frame having substantially parallel portions journaled on the laterally extending part of the axle, means to secure the rear end of the frame to the top of the stock, a blade carrier reciprocable along said parallel portions and urged by said portions toward the roller, a prime mover journaled on one side of the stock, a gear driven by said prime mover to rotate said roller, and a connection from said prime mover to said carrier to reciprocate the carrier.

8. A sharpener of the character described, comprising a stock, a pair of parallel axles each having one of its ends secured to said stock, a member connecting the other ends of said axles and ex-

tending transversely of said axles, a pair of sharpening rollers rotatable, respectively, on said axles, a pair of resilient bars hinged at one of their ends to said transverse member to swing into and out of parallelism with the peripheries of said rollers, interengaging means between said stock and the other ends of said bars for holding said bars in parallelism with the peripheries of said rollers, a blade carrier reciprocable lengthwise of said bars and urged by said bars toward said rollers to maintain the opposite edges of a blade carried thereby in engagement with the peripheries of said rollers, and means including a crank rotatable on said stock for rotating said rollers and reciprocating said blade carrier on said bars.
